CLAIM

The ornamental design for a trailing end of a spinal implant, as shown and described.

DESCRIPTION

FIG. 1 is a perspective view of the trailing end of a spinal implant in accordance with an embodiment of my claimed design with the remainder of the implant shown in hidden line and forming no part of the claimed design;

FIG. 2 is an end view of FIG. 1; and,

FIG. 3 is a side elevational view of FIG. 1 with the remainder of the implant shown in hidden line and forming no part of the claimed design.
